(57) **CLAIM**

The ornamental design for lap desks with device slot, as shown and described.

DESCRIPTION

FIG. 1 is a left, elevated, front quartering perspective view of a first embodiment of a new design for lap desks with device slot;

FIG. 2 is a bottom plan view of the embodiment of FIG. 1; FIG. 3 is a top plan view of the embodiment of FIG. 1; FIG. 4 is a front elevational view of the embodiment of FIG. 1;

FIG. 5 is a rear elevational view of the embodiment of FIG. 1;

FIG. 6 is a right side elevational view of the embodiment of FIG. 1;

FIG. 7 is a left side elevational view of the embodiment of FIG. 1; and

FIG. 8 is a front, elevational section, as indicated in FIG. 3, showing the interior shape of the device slot in the top surface of the embodiment of FIG. 1.

FIG. 9 is a left, elevated, front quartering perspective view of a second embodiment of a new design for a lap desks with device slot;

FIG. 10 is a bottom plan view of the embodiment of FIG. 9; FIG. 11 is a top plan view of the embodiment of FIG. 9; FIG. 12 is a front elevational view of the embodiment of FIG. 9;

FIG. 13 is a rear elevational view of the embodiment of FIG. 9;

FIG. 14 is a right side elevational view of the embodiment of FIG. 9;

FIG. 15 is a left side elevational view of the embodiment of FIG. 9; and,

FIG. 16 is a front, elevational section, as indicated in FIG. 11, showing the interior shape of the device slot in the top surface of the embodiment of FIG. 9.
